HYDRAULIC SQUEEZING AND
DRILLING DEVICEDouglas H. Rowland, 6317 Forest Lane, Dallas, Tex.
Filed Jan. 4, 1960, Ser. No. 275
8 Claims. (Cl. 166—101)

The present invention relates to the oil industry and more particularly to a tool to be used in combination with a fluid circulating drill string, or the like, where high pressures are needed within the bore hole.

In drilling and completing an oil well it is frequently necessary to provide some means for generating a relatively high pressure of the fluid within the bore hole for cementing, squeezing, sand fracturing or other purposes. This high pressure is usually required at or adjacent the formation being cemented off or sand fractured, thus requiring, with most conventional cementing equipment, pressurizing the fluid within the drill string, or the like, from the surface of the hole to the position in the well where the high pressure is needed. Obviously, this requires a considerable amount of fluid as well as high pressure pumps, or the like, in order to generate the required pressure in the drill string of the well.

It is, therefore, the principal object of the instant invention to provide a tool adapted to be connected to a string of drill pipe, or the like, and lowered into a bore hole by which high fluid pressures may be generated within the hole.

Another object is to provide a tool which will generate a hydraulic type of pressure using the fluid circulated through the drill string and which pressure is generated within the tool and applied at or adjacent the point in the bore hole where pressure is desired without pressurizing the fluid in the remainder of the drill string.

Another object is to provide a drilling string tool for generating relatively high fluid pressures within the tool to be applied to the bore hole which will permit passage of the drilling fluid through the tool before and after generating the desired high pressure.

Another object is to provide a tool of this class for use in connection with the drill string wherein the tool will transmit torque, applied to the drill string, to a drilling bit, or the like, on the lowermost end of the tool or on a continuation of the drill string.

The present invention accomplishes these and other objects by providing an elongated sleeve or cylinder within which an elongated centrally bored piston is slidably received. The upper end of the piston is connected with a mandrel slidably received within an adapter for transmitting torque to the cylinder. The upper end portion of the mandrel is threaded for connection with a drill string and includes means releasably engageable with the upper end portion of the adapter for supporting the remainder of the device when running or pulling the latter with the drill string. Valve means, carried by the lower end of the piston, permits circulation of drilling fluid downwardly through the device. The depending end of the cylinder is threaded for connection with a sub-joint which may in turn be connected with a drill string or drilling bit or other tools. The upper end of the sub-joint is provided with valve means which precludes reverse flow of the circulated fluid.

Other objects will be apparent from the following description when taken in conjunction with the accompanying single sheet of drawings, wherein:

FIGURE 1 is a fragmentary elevational view, partly in section, of the upper end portion of the device;

FIGURE 1A is a fragmentary cross-sectional view of the central portion of the device, forming a continuation of the lower end portion of FIG. 1;

2

FIGURE 1B is a fragmentary cross-sectional view, partly in elevation, of the lower end portion of the device, forming a continuation of FIG. 1A;

FIGURE 2 is a horizontal cross-sectional view taken substantially along line 2—2 of FIG. 1;

FIGURE 3 is a horizontal cross-sectional view taken substantially along line 3—3 of FIG. 1A; and

FIGURE 4 is a horizontal cross-sectional view taken substantially along line 4—4 of FIG. 1A.

Like characters of reference designate like parts in those figures of the drawings in which they occur.

In the drawings:

The reference numeral 10 indicates the device, as a whole, which is cylindrical in general configuration. The device 10 includes an elongated cylinder or sleeve 12 threadedly connected, as at 14, with an adapter 16 having an abrupt upper end 18 perpendicular with respect to its longitudinal axis. The adapter 16 slidably receives an elongated mandrel 20 having a central bore 22 therethrough. The periphery of the mandrel, throughout the greater portion of its length, is preferably polygonal, square in the example shown, but which may be elliptical or of any other desired shape. The bore of the adapter 16 is co-operatively formed to slidably receive the mandrel 20. The upper end portion of the mandrel 20 is circumferentially enlarged and elongated, as at 24. This end portion 24 is internally threaded, as at 26, for connection with a drill string, or the like, not shown. The mandrel end portion 24 terminates downwardly in an abrupt shoulder 28 adapted to seat on the upper end 18 of the adapter 16 for the purposes more fully disclosed hereinbelow. The end portion 24 is provided with a plurality, four in the example shown, of latching members 30 which are vertically positioned within a like plurality of vertically elongated slots 32 formed in the end portion 24 and pivotally connected thereto, intermediate their ends, by transverse pins 34. A spring 36 is interposed between the upwardly disposed end of each latch member 30 and the inward surface of the mandrel forming the respective slot 32. The springs 36 are each nested by a co-operative socket 38, formed in the respective latch member, for holding the springs in place. Each of the latch members 30 project downwardly beyond the shoulder 28 and are each formed to define an inwardly directed hook-shape 39 for entering similar co-operatively formed slots 40 formed in the upper end portion of the adapter 16. A pin 42 extends transversely of each of the slots 40 with which the hook portion 39, of each latch, is engaged when the shoulder 28 contacts the adapter end 18 for the purposes more fully described hereinbelow. A pressure actuated plug member 44 is positioned within suitable cylindrical sockets or recesses formed in the wall of the end portion 24 in communication with the bore thereof. The respective plug member has an arcuate end portion 45 in contact with the adjacent surface of the respective latch 30. Each of the plug members 44 are forced outwardly by the drilling fluid, when the latter is under pressure, for maintaining the latches 30 in outwardly disposed pin released position, as shown in FIG. 1. Adjacent its lower end, the mandrel wall is provided with a plurality of ports 23 for communication between the bores of the mandrel 20 and sleeve 12.

The lower end of the mandrel 20 is threadedly connected with an elongated centrally bored piston 46 closely received by the bore of the sleeve 12. A plurality of piston rings 48 seal with the sleeve 12, for the purposes more fully disclosed hereinbelow. A valve head 50 is threadedly connected to the depending end of the piston 46 and is provided with a seat 52 at its lower end. A valve 54, having an axially connected upwardly projecting stem 56, is normally seated on the valve seat 52 by a spring 58 interposed between valve guides 60 and 62.

The valve guide 60 is held in place by the valve head 50 while the guide 62 is freely received by the bore of the piston for vertical reciprocating movement with the valve stem when the valve is opened and closed.

The depending end of the sleeve 12 is threadedly connected with a centrally bored sub-joint 64 having a threaded lower end 66 for connection with a drill string, drill bit, or other tools. Similarly, a valve head 68 is threadedly connected with the upper end of the sub 64 and is similarly provided with a valve seat 70 at its lower end which seats a valve 72 having an upwardly projecting axially connected stem 73, normally held in closed position by a spring 74, similarly interposed between valve stem guides 76 and 78.

Operation

In operation, the upper end portion 24 is threadedly connected to the end of a fluid circulating drill string and lowered into a bore hole, neither of which are shown. When the device is used for a cement squeezing job or sand fracturing a well formation, the appropriate conventional shoe or tool, not shown, is connected with the depending end of the sub-joint 64 and one or more packers, of the type exemplified by United States Patent No. 2,373,005, issued to Baker Oil Tools on April 3, 1945, or any suitable conventional well packer such as those presently available under the trade names of "Halliburton" or "Guiberson," not shown, may be connected with the sleeve 12 at its opposing end portions for positioning the latter at the desired hole depth. Normally only one packer is connected to the sleeve 12 so that fluid pressure may be forced into the annulus of the bore hole below the packer through the sub-joint 64 or through the ports 80. However, when using the device to perform a "squeeze job" through casing perforations a packer set at each opposing end portion of the sleeve limits the area closed off so that cement in a fluid state may be forcibly ejected through the ports 80 to pressure fill such cased off area. When connected with the drill string, the shoulder 28 is positioned in contact with the end 18 wherein the hooks 39 engage the pins 42 to support the sleeve. In this position the device may be used in a conventional manner for drilling, or the like, since torque applied to the drill string is transmitted to the sleeve by the mandrel 20 while a predetermined portion of the weight of the drill string may be applied to the drill bit. When it is desired to use the tool to generate fluid pressure, the drilling operation is stopped and the packer or packers are set, which prevents vertical movement of the sleeve 12 and all of the drill pipe, if any, connected to the sub-joint 64. The drilling mud or fluid, not shown, when circulated under pressure by the conventional mud circulating pumps, forces the plug members 44 outwardly, thus releasing the hooks 39 from contact with the pins and permits the mandrel 20 and piston 46 to be raised so that the upper end portion of the piston 46 is adjacent the lower end of the adapter 16. Drilling fluid circulation is then stopped and the drill string is lowered rapidly whereby the piston 46 compresses the fluid contained by the sleeve 12 and forcibly ejects this fluid through the bore of the sub-joint 64 or other tools. The ports 23 permit fluid, in the annulus between the mandrel 20 and the sleeve 12, to enter the bore of the mandrel 20 as the piston 46 is raised relative to the sleeve. Similarly fluid may enter this annulus, from the bore of the mandrel, when the piston is lowered in its fluid pressurizing function. If desired, ports 80, may be formed in the wall of the sleeve adjacent its connection with the sub-joint 64 for directing a pressurized stream of fluid laterally of the sleeve. Obviously, acid, cement in a fluid state or other fluids may be used in place of the drilling mud or fluid. Downward movement of the piston is limited or stopped by the shoulder 28 contacting the adapter end 18 wherein the latches 30 again engage the pins 42 for pulling the device when removing the drill string from the

hole. This pressuring of the fluid may be repeated as desired without removing the device from the hole.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A hydraulic pressure generating device adapted to be lowered into a well bore on the lower end of a string of fluid circulating drill pipe, comprising: an elongated cylindrical sleeve having a bore of reduced diameter in its upper end portion; pins transversely secured to the upper end portion of said sleeve; a centrally bored mandrel slidably carried within said sleeve and projecting upwardly beyond the upper end portion of said sleeve and adapted to be connected to said drill pipe; a centrally bored piston coaxially connected with said mandrel within said sleeve; closure means carried by the depending end of said piston to prevent fluid flow upward through the bore of the latter when the piston is lowered with respect to said sleeve; piston rings carried by said piston intermediate its ends in sealing contact with the inner wall of said sleeve; and spring urged latch means carried by the upper end portion of said mandrel and engageable with said pins for lifting said sleeve with said mandrel after downward movement of the latter.
2. A hydraulic pressure generating device adapted to be lowered into a well bore on the lower end of a string of fluid circulating drill pipe, comprising: an elongated cylindrical sleeve having a threaded lower end and having a bore of reduced diameter in its upper end portion; pins secured to the upper end portion of said sleeve; a centrally bored mandrel vertically reciprocable in said cylindrical sleeve and closely received by the bore of the reduced diameter, said mandrel adapted to be connected at its upper end with said drill pipe; a centrally bored piston connected with said mandrel within said sleeve; valve means carried by said piston for preventing fluid flow upwardly through the bore of said piston; and spring urged latch means carried by the upper end portion of said mandrel and engageable with said pins for lifting said sleeve with said mandrel after downward movement of the latter.
3. A hydraulic squeezing and drilling device, comprising: an elongated cylindrical sleeve having a bore of reduced dimensions in its upper end portion; pins transversely secured to the upper end portion of said sleeve; a centrally bored mandrel slidably received closely by the reduced bore within said sleeve and extending upwardly beyond the upper end of said sleeve and adapted for connection with the lower end portion of a string of drill pipe; a piston connected with said mandrel within said sleeve and having a valve seat formed on its lowermost end; valve guides within said piston adjacent said valve seat; a valve seated on said valve seat for closing and opening the bore of said piston, said valve having a stem slidably received by said valve guides; spring means interposed between said valve guides for normally maintaining said valve in closed position; a plurality of piston rings carried by the periphery of said piston intermediate its ends; spring urged pivoting latch means carried by the upper end portion of said mandrel and releasably engageable with said pins for lifting said sleeve; with said mandrel after downward movement of the latter; and pressure plug members carried by said mandrel in communication with the bore thereof and in contact with said latch members, said plug members being responsive to fluid pressure within said mandrel for moving said latch members toward pin released position.
4. Structure as specified in claim 3 in which the periphery of said mandrel is substantially square shaped and in which the wall of said sleeve defining the bore of reduced dimensions through said uppermost annular shoulder is co-operatively formed for sliding contact with the surfaces

of said mandrel for rotating said sleeve when said mandrel is rotated by the drill pipe.

5. A hydraulic squeezing and drilling device, comprising: an elongated cylindrical sleeve; an adapter connected to the upper end of said sleeve, said adapter having a square bore, and having a plurality of slots in its upper end portion; pins carried by said adapter and extending transversely through each respective slot therein; a centrally bored mandrel, square in horizontal cross section, slidably received by the bore of said adapter, said mandrel having an enlarged upper end portion adapted to be connected with drill pipe and having a like plurality of outwardly open slots vertically aligned with the slots in said adapter; a like plurality of latch members pivotally supported intermediate their ends within the slots in said mandrel, each said latch member having a hook-shaped end portion depending from the enlarged portion of said mandrel; spring means within each slot in said mandrel above the pivot point of said latch members and normally positioning the hook-shaped end portion of each respective latch member toward engagement with the respective said pin; pressure plug members carried by said mandrel in communication with the bore thereof and contacting the adjacent surface of each respective said latch member, said plug members being responsive to fluid pressure within said mandrel for forcing the hook-shaped end portions of said latch members outwardly toward pin released position; a centrally bored piston connected with the depending end of said mandrel within said sleeve; and valve means carried by the depending end of said piston for preventing upward flow of fluid therethrough when said piston is lowered relative to said sleeve.

6. Structure as specified in claim 5 and a centrally bored sub-joint connected to the depending end of said sleeve; and valve means carried by the upper end of said sub-joint for preventing upward flow of fluid into said sleeve.

7. A hydraulic squeezing and drilling device, comprising: an elongated cylindrical sleeve; an adapter connected to the upper end of said sleeve, said adapter having a square bore, and having a plurality of vertically disposed

slots in its upper end portion; pins carried by said adapter and extending transversely through each respective slot therein; a centrally bored mandrel, square in horizontal cross section, slidably received by the bore of said adapter, said mandrel having an enlarged upper end portion adapted to be connected with drill pipe and having a like plurality of outwardly open slots vertically aligned with the slots in said adapter; a like plurality of latch members pivotally supported intermediate their ends within the slots in said mandrel, each said latch member having a hook-shaped end portion depending from the enlarged portion of said mandrel; spring means interposed between the upper end portion of each said latch member and the wall of said mandrel for pivoting the hook-shaped end of each said latch member toward pin engaging position; pressure plug members carried by said mandrel in communication with the bore thereof and contacting the adjacent surface of each respective said latch member below the pivot point of the latter, said plug members being responsive to fluid pressure within said mandrel for compressing said spring means and maintaining said latch members in released position; a centrally bored piston connected with the depending end of said mandrel within said sleeve; and valve means carried by the depending end of said piston for preventing upward flow of fluid therethrough when said piston is lowered relative to said sleeve.

8. Structure as specified in claim 7 and a centrally bored sub-joint connected to the depending end of said sleeve; and valve means carried by the upper end of said sub-joint for preventing upward flow of fluid into said sleeve.
